HERMANN F. STORRER, OF NEW YORK, N. Y.

SCREEN FOR PAPER-PULP.

1,164,427.

Specification of Letters Patent. Patented Dec. 14, 1915.

Application filed March 2, 1915. Serial No. 11,525.

To all whom it may concern:

Be it known that I, HERMANN F. STORRER, a citizen of the Republic of Switzerland, and residing in the city, county, and State of 5 New York, have invented certain new and Improved Screens for Paper-Pulp, of which the following is a specification.

My invention relates to screens for paper pulp and particularly to an agitator of 10 proved construction adapted not only to prevent clogging of the screen but also to aid the screening action and thus to increase the capacity of the apparatus and the quality of the product.

15 An illustrative embodiment of my invention is shown in the accompanying drawings in which—

Figure 1 is a plan of a rotary screen showing my improved agitator associated therewith; Fig. 2 is a longitudinal section therethrough; Fig. 3 is an end elevation of the same; Fig. 4 is a transverse section of the same; and Fig. 5 is a diagram illustrating the movement of the agitator.

20 The common practice in the paper making industry is to comminute the material from which the paper is to be made *e. g.* wood or suitable fiber,—and pass the same in liquid suspension, through a screen of suitably fine 25 mesh or grid, to eliminate coarse fibers, lumps, knots, etc., which would be unsuitable for use in the grade of paper which is to be made. One of the difficulties in this process is to prevent the clogging of the screen 30 apertures since the capacity of the apparatus is at once lowered when this takes place. Furthermore, the pulp stock contains fibrous as well as filler elements, and it is highly desirable that these constituents of the paper 35 pass through the screen in normal, uniform quantity so that they are mingled in proper proportion in the screened suspension, since the quality and even texture of the paper is affected thereby. The pulp stock to be 40 screened must therefore be kept agitated so that these elements are uniformly mingled 45 therein.

The present invention affords an agitator 50 which not only serves to keep the screen apertures clear but also to maintain the suspension uniform while at the same time it assists the screening action in a manner pointed out hereinafter.

55 In the apparatus here illustrated, the pulp stock or suspension α is fed as usual to a vat 10 through an intake port 11. The slowly

rotating cylindrical screen 12 is supported within the vat by hollow hubs 13 closed at their outer ends by the stationary heads 14, through ports 15 in which the screened pulp 60 suspension γ flowing into the screen from the vat passes out to the paper making machinery. Gear rings 16 on these hubs mesh with pinions 17 on the shaft 18, driven through gear 19, the latter rigid with the 65 worm gear 21 engaged by the worm 22 on the shaft of the pulley 23 which in turn is driven by belt 24 from pulley 25 on the first motion shaft 26 carrying fast and loose pulleys 27, 28. A spray pipe 29 passes longitudinally through the screen above the level of the suspension therein and directs jets of water, under heavy pressure, upward through the screen apertures, thus washing 75 into the off-take pipe 30 any coarse material 75 which may have adhered to the outer surface of the screen.

The agitator, with which the present invention is especially concerned, is suspended in the vat below the lower portion of the 80 rotary screen. In the form here shown, the screen comprises a reticulated plate 31 extending the length of the screen and having a curvature substantially corresponding to that of the screen. It is suspended by pairs 85 of arms 32 and 33 carried up over the opposite sides of the vat and terminating on the one side in bearing rings 34 surrounding adjustable eccentrics 35 mounted on shaft 26, and on the other side in a joint rigid with 90 the upper ends of a pair of vertically arranged leaf springs 36. The latter are bolted at 37 to bosses 38 cast on the side of the vat. Adjusting screws 39 which bear against 95 straps 40 on the springs, may be provided to afford means for varying the action of the springs, for example, by shortening the working length thereof, or by imparting an initial tension thereto. Tie rods 41 extending between sockets 42 on the arms of each 100 pair of suspension arms 32, 33 further strengthen and add rigidity to the cradle-like structure.

When the shaft 26 is driven, the cams 35 impart an oscillating motion to the agitator 105 which is diagrammatically shown in Fig. 5. Near the eccentric all the points move in an approximate circle. The farther from the eccentric and toward the spring support, the less becomes the vertical oscillation. The 110 motion is illustrated by ellipses, the vertical short diameter of which grows less and less

as the spring support is approached. This movement, which is a compound of vertical and lateral motions, effects a continuous agitation of the pulp stock in the vat and thus 5 insures the uniform distribution of the fiber and filament elements throughout the stock,— a feature of importance as above pointed out.

The oscillatory movement of the agitator 10 plate, first toward and then away from the cylinder screen, creates alternate pressure and suction efforts with relation to the latter which are of great importance. Thus the pressure effort, on the approach of the screen 15 to the cylinder causes the suspension liquid and fine pulp elements to pass with abnormal rapidity through the screen apertures, thus accelerating the action of the screen and increasing the capacity of the apparatus. The suction effort on the other hand, 20 serves to draw off the screen surface the coarse particles retained thereby and thus clears the screen apertures and keeps the latter at its maximum capacity for the work 25 demanded of it.

The action of the agitator is rendered particularly effective by making the plate of such size that it extends from end to end of the cylinder screen, while its upper edges 30 lie only so far below the surface of the pulp stock in the vat as may be necessary to avoid splashing.

The extent of movement of the agitator can be regulated by adjusting the eccentric 35 to give a greater or less throw. The speed of rotation of the eccentric which will give the best result, varies with the pulp stock in the vat. It should be such however, that the pressure and suction efforts are well 40 defined, if the best results are to be secured.

The spring is preferably so arranged that it tends constantly to press the vibrator in one direction and the cam has to overcome its effort in one direction only. A silent 45 operation of the device without unnecessary wear upon the parts is secured by this arrangement.

Various modifications of construction will readily suggest themselves by which the same

result may be accomplished but which do not 50 depart from what I claim as my invention.

I claim as my invention:—

1. In a pulp screening apparatus, a vat for pulp stock, a rotary screen within the vat, an agitator dipping into the stock beneath 55 the screen and extending upward on opposite sides thereof, and a spring support for one side of said agitator.

2. In a pulp screening apparatus, a vat for pulp stock, a rotary screen within the 60 vat, an agitator dipping into the stock beneath the screen and extending upward on opposite sides thereof, a vibratory device operatively connected to one side of said agitator and a spring support for the opposite 65 side of said agitator.

3. In a pulp screening apparatus, a vat for the pulp stock, a rotary screen within the vat, an agitator dipping into the stock beneath the screen and curved to curvature 70 of the screen, supports for said agitator extending outside the vat on opposite sides of the screen, cam means operatively connected to the support on one side of the screen for moving the agitator in one direction and 75 spring means operatively connected to the support on the opposite side for moving said agitator in the other direction.

4. In a pulp screening apparatus, a vat for the pulp stock, a rotary screen within the 80 vat, an agitator dipping into the stock and extending outside the vat on opposite sides of the screen, and a spring support for one end of said agitator.

5. In a pulp screening apparatus, a vat for the pulp stock, a rotary screen within the 85 vat, an agitator dipping into the stock and extending outside the vat on opposite sides of the screen, and a tensioned spring support for one end of said agitator. 90

In testimony whereof I have signed my name to this specification, in the presence of two subscribing witnesses.

HERMANN F. STORRER.
